AUTOMOBILE OIL CHANGER OR SIMILAR ARTICLE

Ernest K. Gentit, Stryker, Ohio, assignor to The Aro
Corporation, Bryan, Ohio, a corporation of Ohio

Filed Dec. 10, 1962, Ser. No. 72,778

Term of patent 14 years

(Cl. D46—1)

FIG. 1 is a perspective view of an automobile oil changer or similar article showing my new design;

FIG. 2 is a top plan view thereof, and

FIG. 3 is a side elevational view thereof.

The dominant features of my design reside in the portions shown in full lines.

I claim:

The ornamental design for an automobile oil changer or similar article, substantially as shown and described.
